DESIGN FOR A MAGNIFIER APPARATUS

George Scherr, Brooklyn, N. Y.

Application September 17, 1941, Serial No. 103,391

Term of patent 14 years

To all whom it may concern:

Be it known that I, George Scherr, a citizen of the United States, residing at 20 Plaza Street, Brooklyn, county of Kings, and State of New York, have invented a new, original, and ornamental Design for a Magnifier Apparatus, of which the following is a specification, reference being had to the accompanying drawing, forming part thereof.

Fig. 1 is a plan view of a magnifier apparatus, showing my new design; and

Fig. 2 is a side view thereof, the opposite side having substantially the same appearance as the side shown.

I claim:

The ornamental design for a magnifier apparatus, substantially as shown and described.

GEORGE SCHERR.
